HANDLEBAR FOR BICYCLES

Philip Steller, 75 Longfellow Road,
Great Neck, N.Y. 11023

Filed Dec. 14, 1967, Ser. No. 9,784

Term of patent 14 years

(Cl. D90—11)

FIG. 1

FIG. 1 is a side elevational view of a handlebar for bicycles showing my new design;

FIG. 2 is a front elevational view thereof; and

FIG. 3 is a top plan view thereof.

The stem, shown fragmentarily and in broken lines in FIGURE 1, is included for illustrative purposes only.

I claim:

The ornamental design for a handlebar for bicycles, substantially as shown and described.
